FOOD MIXING BOWL

John Phillip Johnson, Montrose, N.Y., assignor to Corning Glass Works, Corning, N.Y., a corporation of New York

Application May 17, 1957, Serial No. 46,219

Term of patent 14 years

(Cl. D44—15)

Fig. 1 is a top plan view of a food mixing bowl embodying my new design.

Fig. 2 is a sectional view taken on line 2—2 of Fig. 1.

I claim:

The ornamental design for a food mixing bowl, as shown.
